UNITED STATES PATENT OFFICE.

EDWIN LIONEL BLAKE AND ROBERT HENRY PLATT, OF OLDHAM, ENGLAND;
ASSIGNORS TO "GNU" PEN (AND PATENTEES) COMPANY, LIMITED, OF
OLDHAM, ENGLAND.

FOUNTAIN OR RESERVOIR PEN.

SPECIFICATION forming part of Letters Patent No. 718,417, dated January 13, 1903.

Application filed August 25, 1902. Serial No. 120,991. (No model.)

To all whom it may concern:

Be it known that we, EDWIN LIONEL BLAKE and ROBERT HENRY PLATT, subjects of the King of Great Britain, residing at Oldham, 5 England, (whose post-office addresses are respectively 66 Belgrave road and 215 Ashton road, both of Oldham, in the county of Lancaster, England,) have invented a new and useful Improved Fountain or Reservoir Pen, (for which we have made application for a patent in Great Britain, No. 23,988, dated November 26, 1901,) of which the following is a specification.

Our invention relates more particularly to improvements in that class of fountain or reservoir pens in which a "piston" is employed for the purpose of charging the reservoir with ink and feeding the pen therewith, its object being to provide means whereby such pens 20 are rendered more reliable, simple, and effective than has heretofore been done.

According to our invention the pen is provided with a special locking device at the outer end of the ink-reservoir and piston end, 25 and thereby enables the piston to be locked in position when drawn out after charging the reservoir with ink. The feeder also is so arranged that while any ink remains in the reservoir it is always in contact with the ink, 30 the piston having concentrically a bore which the feeder enters. We attain these objects by the mechanism illustrated in the accompanying drawings, in which—

Figure 1 is an elevation, and Figs. 3 and 5 longitudinal sections, of our improved pen complete, Figs. 1 and 3 showing the piston in its outer, and Fig. 5 in its inner, position. Fig. 7 is a side view of the feeder separate; Figs. 2, 4, 6, and 8, cross-sections at lines A A, B B, 35 C C, D D of Figs. 1, 3, 5, and 7, respectively.

Similar letters refer to similar parts throughout the several views.

In carrying out our invention and referring to the figures generally our improved locking device consists, preferably, of a nut *a*, screwed into the end of the ink-reservoir *b*, through which the piston-rod *c* passes, the hole in the inner half *d* of this nut being bored out slightly larger than the other or outward half *e* and screwed or tapped, and the piston and rod *c* having a bore *c'*, while the piston-rod

itself is formed with a screwed shoulder *f* at the end nearest to the piston *g*, which shoulder extends about one-quarter of an inch in length, the said internal screw-thread being 55 adapted to receive the said screw-threaded shoulder *f* when the piston has been drawn out to its full extent. (See Fig. 3.) The outward nut-half *e* is also screw-threaded and adapted to receive a cap *h*, correspondingly 60 screw-threaded internally and providing a space for an india-rubber or other suitable packing *i*, forming an air-tight joint between the nut *a* and piston-rod *c*. By a few turns to the right the piston *g* is thus locked in its 65 outer position in the reservoir *b* and precludes the possibility of an escape of ink through the piston becoming unlocked and accidentally forced inward, and the outer cover *k* is also at the same time made rigid. The outer end of 70 the said piston-rod has secured to it a knob *l*, to which is screwed the respective end of the outer cover *k*, which fits and is adapted to slide over the cap *h*, nut *a*, and reservoir *b*.

The ink-feeder *m* used is fitted into the nib-nozzle *n* of the pen and consists of a tube of vulcanite or other kind of material, the outer end of which projects into the ink-reservoir *b* and enters the bore *c'* of the piston *g* when the same is in its inner position. (See Fig. 80 4.) The outer end of the said piston has perforations *p*, so as to cause the ink not only to enter the feeder at the end, but also at the sides thereof. The inner end of the said feeder is split into two parts, which are slightly 85 cranked, one thereof being adapted to fit upon the top of and the other underneath the pen-nib *o*.

What we claim as our invention, and desire to secure by Letters Patent, is—

1. In a fountain or reservoir pen, an ink-reservoir having at its outer end an internally-screw-threaded part, a piston in said reservoir having a rod passing through said screw-threaded part, said rod having near 95 the piston a threaded shoulder adapted to engage said internal screw-thread to lock the piston in a retracted position, substantially as described.

2. In a fountain or reservoir pen, an ink-reservoir, a threaded nut secured to its outer end, a piston in the said reservoir the rod of

which passes through the said nut and which near the said piston is formed with a screw-threaded shoulder adapted to engage in the said nut and lock the piston to the said reservoir, all combined substantially as and for the purpose set forth.

3. In a fountain or reservoir pen, an ink-reservoir, a piston therein having a concentric bore, means for locking the said piston in its outer position to the said reservoir, a pen-nib nozzle at the inner end of the latter,

a feeder in the latter projecting into the reservoir and bore of the said piston when in its inner position, all combined substantially as and for the purpose set forth. 15

In witness whereof we have hereunto set our hands in presence of two witnesses.

EDWIN LIONEL BLAKE.
ROBERT HENRY PLATT.
